(57) **CLAIM**

The ornamental design for a tissue cleaner, as shown and described.

DESCRIPTION

FIG. 1 is a front view of a tissue cleaner according to an embodiment of the new design;

FIG. 2 is a right view thereof;

FIG. 3 is a left view thereof;

FIG. 4 is a top view thereof;

FIG. 5 is a bottom view thereof;

FIG. 6 is a front-right-bottom perspective view thereof;

FIG. 7 is a magnified view of a portion of the tissue cleaner shown in FIG. 6;

FIG. 8 is a front-left-bottom perspective view thereof;

FIG. 9 is a magnified view of a portion of the tissue cleaner shown in FIG. 8;

FIG. 10 is a front view of a tissue cleaner according to another embodiment of the new design;

FIG. 11 is a right view thereof;

FIG. 12 is a left view thereof;

FIG. 13 is a top view thereof;

FIG. 14 is a bottom view thereof;

FIG. 15 is a front-right-bottom perspective view thereof;

FIG. 16 is a magnified view of a portion of the tissue cleaner shown in FIG. 15; and

FIG. 17 is a front-left-bottom perspective view thereof; and,

FIG. 18 is a magnified view of a portion of the tissue cleaner shown in FIG. 17.

The dashed broken lines in the figures show portions of the tissue cleaner that form no part of the claimed design.

The dot-dash broken lines in the figures show boundaries that form no part of the claimed design.

* cited by examiner

A perspective view of a decorative ribbon or cord. The cord is composed of a series of small, raised, rounded, and slightly irregular shapes that create a textured, woven-like appearance. The cord is shown from a slightly elevated angle, highlighting its three-dimensional structure and the pattern of its raised segments.
